UNITED STATES PATENT OFFICE

173,181

VACUUM CLEANER

Albert Bill, Basel, Switzerland, assignor to
Tornado A.-G., Basel, Switzerland

Application November 4, 1952, Serial No. 22,125

Term of patent 7 years

(Cl. D9—2)

To all whom it may concern:

Be it known that I, Albert Bill, citizen of Switzerland, residing at Basel, Hardstrasse 36, Switzerland, have invented a new, original, and ornamental Design for a Vacuum Cleaner, of which the following is a specification, reference being had to the accompanying drawing, forming part thereof.

Fig. 1 is a perspective view from one side of a vacuum cleaner, showing my new design;

Fig. 2 is a perspective view thereof from the other side; and

Fig. 3 is a bottom view of a vacuum cleaner, showing my new design.

I claim:

The ornamental design for a vacuum cleaner, substantially as shown.
